UNITED STATES PATENT OFFICE.

BENJAMIN H. LEISTER, OF SAN FRANCISCO, CALIFORNIA.

STEAM-GENERATOR.

1,383,408.

Specification of Letters Patent.

Patented July 5, 1921.

Application filed November 7, 1918, Serial No. 261,731. Renewed February 19, 1920. Serial No. 359,848.

To all whom it may concern:

Be it known that I, BENJAMIN H. LEISTER, a citizen of the United States, residing in the city and county of San Francisco and State of California, have invented a new and useful Improvement in Steam-Generators, of which the following is a specification.

My invention relates to improvements in steam generators of the so-called "flash" type, wherein parallel convolute walls operate to form parallel alternating water and heat passages.

The primary object of my invention is to provide an improved and simplified construction for steam generators whereby greater strength and efficiency may be obtained.

A further object of the present invention is to provide a multi-channelled steam generator constructed in such a manner that the numerous parts may be rigidly and securely welded together during formation whereby leakage of joints may be prevented.

It is also an object to provide a steam generator of simple and improved construction having a maximum heating area whereby efficiency may be obtained.

A still further object of the present invention is to provide a new and improved steam generator formed of parallel convolute walls coiled to form convolute parallel passages for conveying heat and water in such a manner that a thin film of water will be exposed to the heat.

I accomplish these several objects by means of the device disclosed in the drawing forming a part of the present specification wherein like characters of reference are used to designate similar parts throughout the said specification and drawings, and in which—

Figure 1 is a horizontal transverse sectional view of my improved generator;

Fig. 2 is a vertical sectional view taken on line 2—2 of Fig. 1, in the direction indicated;

Fig. 3 is a horizontal sectional view of the parallel walls in an extended or straightened position; and

Fig. 4 is a front elevation of Fig. 3 with the near wall removed.

Referring to the drawings the numeral 1 is used to designate a sheet of metal bent upon itself to form parallel walls 1 coiled upon a central member 2, having a central passage or bore 3 for the passage of heat, to

form a thin convolute water passage 4 for the conveyance of a thin film of water or other element to be heated, and a parallel convolute passage 6 for the conveyance of heated gases from a combustion chamber hereinafter more fully described.

As the walls 1 are coiled, it is evident that continuous alternate convolute water and heat passages 4 and 6 respectively, will be provided.

The water passage 4 is provided with an inlet 7 at the inner end and an outlet 8 at the outer end thereof.

The water passage 4 is also provided with a series of intercalated partitions 11, certain of which are provided with vertically disposed extensions 12 to form a continuous convolute channel having pockets to form traps whereby the water in the upper portions of said channel will be trapped in the same manner and for the purpose well known to the state of the art.

The heat passage 6 is provided with a series of apertured separators 14 whereby the spaced relation of the walls 1 to form said passage 6 is maintained.

These separators 14 in conjunction with the partition 11, also serve as binders to resist the lateral pressure and strain upon the walls 1 in the water passages.

A suitable combustion chamber 16 is arranged under the entire structure, said chamber 16 being connected with a fuel supply chamber 17 by means of suitable burner 90 aperture 18.

In operation the water is admitted through the intake 7 to the uppermost portion of the water passage 4 and flows in a thin film as provided by the space between the walls 1 through the channel formed by the partitions 11 from the inner to the outer end of the convolute passage 1 at which point it flows into the next lower channel and back to the inner end of the convolute passage 1 where it encounters the first trap or extension 12 of that partition 11, and so on, back and forth, from the inner to the outer end, and from the outer to the inner end of the convolute passage 4, the temperature of the said water being constantly increased by the passage of heat through the convolute heat passage 6 until steam is formed in the lowermost channel between the lowermost partition 11 and the bottom of the structure.

It is obvious that the water being in the form of a thin film will be quickly heated

in its downward passage until it is transformed into steam at the bottom of the generator where the greatest amount of heat exists so that said water is transformed into a dry steam by the time it reaches the bottom of the generator.

It is also obvious from the foregoing that by means of the parallel convolute heat and water passages 6 and 4 respectively, the greatest possible heating area has been obtained with a comparatively simple and efficient construction and arrangement.

Having thus described my invention, what I claim as new and desire to secure by Letters Patent is—

1. A steam generator comprising parallel convolute walls arranged to provide alternate parallel water and heat passages; means within the convolute water passage for providing continuous alternating channels from one end of said passage to the other; and means for trapping water at one end of said channel.

2. A steam generator comprising parallel convolute walls arranged to provide alternate parallel water and heat passages; means within the convolute water passage for providing continuous alternating channels from one end of said passage to the other; and suitable convolute separators within the heat passages.

3. A steam generator comprising parallel convolute walls coiled to form alternate parallel water and heat passages; intercalated convolute partitions arranged within the water passages to form alternating channels and water traps whereby a forced circulation of water within said passage may

be obtained; and apertured convolute separators arranged within the heat passage. 40

4. A steam generator comprising parallel convolute walls coiled to form alternate parallel water and heat passages having an intake at the inner end and a discharge at the outer end of the water passage; intercalated convolute partitions arranged within the water passage and bent upwardly adjacent the outer end of the water passage to form continuous alternating channels and water traps whereby a forced circulation of 50 water within said water passage may be obtained; and apertured convolute separators arranged within the heat passage.

5. A steam generator comprising parallel walls arranged to provide alternate continuous circuitous water and heat circulating passages, devices situated in spaced relation within the water passage for providing continuous alternating channels throughout the length of said passage, said device affording 60 a trap in certain of said passages and spaced separators arranged within the heat passage intermediate the ends thereof.

6. A steam generator comprising parallel convolute walls arranged to provide a convolute passage for a water film and alternating convolute heat passages, devices situated in spaced relation within the water passage for providing continuous alternating channels throughout the length thereof, and perforated separators arranged in spaced relation within the heat circulating passage. 70

In witness whereof I hereunto set my signature.

BENJAMIN H. LEISTER.
